UNITED STATES PATENT OFFICE.

FRANK A. LINDSTROM, OF ST. PAUL, MINNESOTA.

PADDLE BOAT.

Application filed October 29, 1927. Serial No. 229,614.

This invention relates to paddle boats of a type adapted particularly to be used as amusement devices at beach resorts and similar places.

5 It is the object of this invention to provide a novel paddle boat within which an operator may sit and paddle about in the water. To this end, the invention consists in the novel parts and novel combinations of parts hereinafter defined in the claims and described in the following specification made in connection with the accompanying drawings, wherein like reference characters refer to the same or similar parts throughout the 10 various views and, in which,

Fig. 1 is a plan view of the paddle boat;
 Fig. 2 is a vertical section taken on the line 2—2 of Fig. 1, as is indicated by the arrows;
 20 Fig. 3 is a vertical section taken on the line 3—3 of Fig. 1, as is indicated by the arrows and
 Fig. 4 is a vertical section taken on the line 4—4 of Fig. 1, as is indicated by the arrows.

25 Referring to the drawings, a pair of long floats 5 are provided which are preferably air floats of tubular construction and having pointed closed forward ends and closed rear ends. The floats 5 are arranged in parallel spaced relationship and each float has secured thereto by straps 6 a bar 7 at its upper side. Bars 7 are secured together by suitable bracing such as rear transverse bar 8 and the forward transverse bars 9, 30 in turn, secured together by longitudinal bars 10. Secured forward of the center of each of the bars 7 is a slotted keeper 11, while spaced rearwardly from the keepers 11 staples 12 are secured to the bars 7. Sliding bolt latches 13 of the conventional type are secured to the bars 7 adjacent each of the staples 12 so that the bolts of the latches may be engaged or disengaged within the staples 12. Bearing blocks 14 are placed on 35 the bars 7 between keepers 11 and staples 12 and are adapted to be fixed in place by means of U-shaped bars 15 which are adapted to extend over the said bearing blocks and each of which has one end adapted to fit within the slot on one of the keepers 11 and another hasp-like end having a slot therein so that the end can be placed over the staple 12, whereupon the bolt of the latch 13 may be slid through the staple to securely hold and 45 retain the bar 15 and the bearing block 14

in place. A pair of spaced strap bearings 16 are secured to each bearing block 14 and have journaled therein a crank shaft 17 provided with a crank portion 17^a inwardly from the float to which its respective bearing block is secured. Outwardly from each of the bearing blocks 14, each of the crank shafts 17 has secured thereto a pair of spaced heads 18 carrying a plurality of radial arms 19. Transverse slats 20 extend between and are secured to adjacent arms 19 mounted in the two heads secured to each shaft 17. The heads 18, arms 19 and slats 20 for each shaft 17, form a paddle wheel projecting outwardly from the strap bearings 16 at the 60 outer side of a repetitive float.

Channel-shaped track members 21 are secured to each of the bars 7 rearwardly from the crank shaft 17 so that the track members extend over the side edges of the bars. A transverse seat 22 having a back 23 secured thereto by suitable brackets 24 extends between the bars 7 and is suitably mounted by brackets 25 on the track members 21 for sliding movement over the same. 75 Two of the brackets 25 are secured to each end of the seat 22, project upwardly therefrom and then extend horizontally over the two track members 21 on each bar 7 and each bracket is provided with a hooked portion at its upper outer end hooked over one of the outer track members 21. As is illustrated in Fig. 3, the brackets 25 are so constructed that although they are capable of sliding movement on the track members 21, they cannot be disengaged therewith to 80 permit removal of the seat 22.

85 The crank shafts 17 inwardly from the crank portions 17^a are provided with grooves 17^b adjacent their ends and a sleeve 26 fits over the two inner ends of the two crank shafts and is provided with a pair of screws 27 projecting inwardly from the sleeve and fitting within the grooves 17^b to hold the crank shafts from lateral movement. The 90 screws 27 do not normally engage the inner ends of the crank shafts 17 so that the two crank shafts can rotate independently of each other and independently of the rotation of sleeve 26. Hand grip members 28 are loosely mounted on the crank portions 17^a of the crank shafts 17.

100 Forwardly of the crank shafts 17 and at the inner sides of each of the floats 5, there are secured a pair of blocks 29 adapted to 105

be used as leg supports by the operator of the boat. The blocks 29 are secured to the bars 7 by means of suitable brackets 30.

In operation, the operator of the boat will sit upon the seat 22 and rest the calves of his legs on the blocks 29. By sliding the seat 22 toward or from the crank shafts 17, he may adjust himself in a position convenient for readily grasping the hand grip members 28. The operator can then grasp the hand grip members 28 and rotate the same, thereby causing the crank shafts 17 to be rotated to turn the paddle wheels and propel the boat. Due to the fact that the two shafts 17 are capable of independent rotation, it will be seen that one paddle wheel can be forwardly rotated while the other wheel remains stationary or is rearwardly rotated. It will thus be apparent that the boat can be readily steered in the water and that the same can be sharply turned or reversed. The operator sitting in the seat 22 will rest partly in the water and partly above the water. The boat will thus have a low center of gravity and cannot be readily tipped over when in use. By actual tests, the inventor found that it is almost impossible to tip over the boat even on very windy days. Due to the fact that the bracket plates 14 may be removed from the bars 7, it will be seen that the entire crank shaft and paddle wheel construction can be taken off the boat. The boat then will be capable of operation only as a raft. When so disassembled, the device may be readily shipped or stored.

The inventor contemplates the use of the paddle wheel and crank shaft assembly, not only on boats of the nature above described but also on row boats or other small skiffs.

It will, of course, be understood that various changes may be made in the form, de-

tails, arrangement and proportions of the various parts without departing from the scope of the present invention.

What is claimed is:

1. A paddle boat having in combination a pair of floats secured together in spaced relationship, a slotted keeper mounted on each float, an eye mounted on each float, a latch mounted on each float and adapted to be releasably engaged in one of said eyes, a bearing adapted to be placed on each float between the keeper and the eye thereon, a U-shaped bar for each float having one end adapted to be placed within the slot in one of said keepers and another hasp like end adapted to be fitted over one of said eyes, said bar being adapted to fit over one of said bearings and to be held in place by one of said latches, a crank shaft journaled in each bearing and having a crank portion adapted to extend inwardly from its respective float and a portion extending outwardly therefrom, a paddle wheel secured to the outwardly extending portion of each crank shaft and a seat adapted to be secured rearwardly from said crank shafts between said floats.

2. A paddle boat having in combination a pair of floats secured together in spaced arrangement, latching means in each float, a bearing block adapted to be releasably secured to each float by said latching means, a crank shaft journaled in each bearing block and having a crank portion adapted to extend inwardly from its float, and a portion extending outwardly from its float and a paddle wheel secured to each outwardly extending portion of said crank shafts.

In testimony whereof I affix my signature.

FRANK A. LINDSTROM.
